POMPEIN BOSCH, OF ELGIN, ILLINOIS.

BORING-MACHINE.

1,373,856.

Specification of Letters Patent.

Patented Apr. 5, 1921.

Application filed July 18, 1919. Serial No. 311,761.

To all whom it may concern:

Be it known that I, POMPEIN BOSCH, a citizen of the Republic of Hungary, residing at Elgin, in the county of Cook and State of Illinois, have invented certain new and useful Improvements in Boring-Machines, of which the following is a specification.

My invention relates to boring machines by the use of which engine cylinders can be reboored without removal of the crank shaft and without taking the cylinder block out of its bearings in the frame of an automobile. The primary object of the invention is the provision of an improved machine of this kind, easily centered and placed in position for boring, and so constructed and arranged that those operating parts normally working within the cylinder to be bored may, during the process of boring, be quickly removed from the cylinder to permit inspection of the work. Another object lies in the provision of an improved tool holding device whereby the cutting tool of the machine may be held very rigidly to its work and may also be quickly advanced toward or withdrawn from the work. In connection with the last named object, it is also my intention to provide a device for boring machines whereby the tool may be adjusted toward or from the work through extremely small distances and with great accuracy. A further object is to provide an improved form of connection between a tool holder and the device whereby the same is actuated. A further object is to devise a very compact boring machine.

Other objects and advantages of the invention will appear from the following description, taken in conjunction with the accompanying drawings which form a part of this specification and illustrate the preferred embodiment of the invention.

In the drawings:

Figure 1 is a section taken axially through a two-cylinder gas engine casting, illustrating the present invention mounted in operative position on the casting and partially sectioned in approximately the plane defined by the axes of the casting cylinders.

Fig. 2 is a section of a portion of the invention taken on line 2—2 of Fig. 1, omitting the cylinder casting.

Fig. 3 is a view in perspective of a catch plate forming a part of the invention.

Fig. 4 is a fragmentary bottom plan view

of the preferred form of tool holder illustrating the device whereby the tool is rigidly held to its work, quickly advanced to and withdrawn from the same, and adjusted with respect to the work through very short distances and with great accuracy.

Fig. 5 is a section taken approximately on line 5—5 of Fig. 4.

Reference numeral 10 indicates generally a cylinder casting for a gas engine comprising piston cylinders 11 and 12, the present invention being shown in Fig. 1 positioned for boring cylinder 11. The frame of the present invention is adapted to be bolted to the cylinder casting by means of any suitable number of machine bolts 13, which engage the tapped holes always provided for the bolting of the cylinder heads to the cylinder. This frame comprises a frame plate 14 overlying cylinder 12 and formed integrally with a depending post 15 which is rigidly positioned axially within cylinder 12 and projects below the bottom of the latter. An arm, 16, is bolted upon the top of frame plate 14 by bolts 17 which traverse holes 18 formed in the arm; these holes being of greater diameter than that of the bolts 17, so that arm 16 may be shifted horizontally to cause its tool bearing extremity 19 to be accurately centered with respect to cylinder 11 over which it stands. The bottom surface 20 of post 15 defines a plane standing at right angles to the parallel axes of cylinders 11 and 12, and a supporting plate 21 is rigidly bolted against the surface 20. Plate 21 is held against post 15 by a machine bolt 22 which passes through a hole 23 of greater diameter than the bolt, so that the plate may have its free extremity 24 accurately positioned concentric with the axis of cylinder 11.

The extremity 19 of arm 16 forms the upper bearing for a tool shaft 25, the lower end of which bears in the extremity 24 of the supporting plate 21. For reasons which will be obvious from the further description the extremities 19 and 24 are spaced respectively above and below the upper and lower ends of the cylinder to be bored. The upper end of shaft 25 is enlarged to form a head 26 which revolves upon the top of arm 16. The head 26 is provided with a peripheral channel 27 which is engaged by a finger 28 bolted to the arm 16. Fixed in any suitable manner to head 26 are radiating handles 29 by means of which the tool

shaft 25 is rotated. Finger 28 fits slidably within channel 27 and holds the head 26 against arm 16. By loosening the bolt 31 which holds the finger to arm 16, the finger 5 may be turned out of channel 27 so that it forms no impediment to the withdrawal of tool shaft 25 from its bearings. Slidably and rotatably mounted upon the tool shaft are upper and lower frusto-conical centering disks 32 and 33 respectively, the upper disk 32 resting by gravity in the upper end of cylinder 11, and the lower disk 33 being held in the lower end of that cylinder by helical spring 34 which is interposed between the bottom of the disk and the top of 10 supporting plate 21 and surrounds the tool shaft.

The tool shaft 25 is provided with a longitudinal channel 35 which opens inwardly 20 from its outer surface and extends parallel with its axis. A feed screw 36 is positioned in channel 35 and is journaled at its upper end in the head 26. The upper end of the feed screw extends slightly above the head 25 26 and is there provided with the hand crank 37. The lower end surface of tool shaft 25 defines a plane standing at right angles to the tool shaft and the axis of cylinder 11, the tool shaft protruding slightly 30 below the bottom of supporting plate 21, as seen in Fig. 1. A short boss 38 is formed on the bottom of supporting plate 21 and projects below the plate the same distance as does the tool shaft 25, the bottom surface 35 of the boss lying in a common plane with bottom surface of the tool shaft.

A machine bolt 39 has its threaded end engaged in a tapped aperture which extends from the bottom surface of boss 38 upwardly into the supporting plate 21, the head of this bolt being spaced below the bottom surface of the boss. Mounted to slide between the head of bolt 39 and boss 38 and to oscillate with respect to the bolt, 40 is a supporting bar 41 in the free extremity 42 of which is journaled the reduced lower end 43 of the feed screw 36. The shank of bolt 39 passes through an elongated slot 44 formed in the supporting bar. The feed 45 screw 36 is eccentrically positioned in the tool shaft 25 and is carried bodily in an annular path during the rotation of the latter. The free extremity 42 of the supporting bar 41 follows this annular path, the 50 bar oscillating slightly about bolt 39 and sliding smoothly in its seat between the head of the bolt and boss 38. Thus the supporting bar 41 forms a support for the lower end of the feed screw 36.

60 A feed nut 45 travels upon the feed screw 36 and slidably fits between the opposite parallel sides of the channel 35. A circular tool carrier 46 slidably fits about the tool shaft 25 and carries a cutting tool 47 which, 65 if desired, may be of any ordinary form

and secured in a suitable channel provided in the tool carrier by means of an ordinary bolt 48—this form of mounting being illustrated in Figs. 1 and 2. A squared recess 49 is provided in the tool carrier and intersects the upper and inner surfaces thereof. In this recess is snugly fitted a catch block 51, the latter being formed with a mortise 52 which projects toward the center of the tool shaft 25 and fits a tenon provided in 70 the outer side of feed nut 45. For the purpose of retaining the catch block in its recess, I provide upon the upper surface of the tool carrier an arcuate catch plate 53 which is provided near its ends with arcuate 75 slots 54 engaged by the shanks of a pair of bolts 55. During the operation of the machine the position of the catch plate is that indicated by dotted lines in Fig. 2, a portion of the plate overlying the catch block. 80 Near its center, however, the inner edge of the catch plate is intersected by an aperture 56 formed in the plate and of the same shape and size as the catch block 51. When it is desired to release the connection between the feed nut and the tool carrier, the bolts 55 are loosened and the catch plate is shifted to the full line position shown in Fig. 2. In this position of the parts the aperture 56 of the catch plate registers 85 above the recess 49 of the tool carrier and the tool carrier drops onto the top of the lower centering disk 33, following which the catch block 51 may be withdrawn from its tenon and mortise connection with the feed nut 45; and the tool shaft 25, feed screw 36, and feed nut 45, may be drawn upwardly out of the frame and cylinder, after the removal of finger 28 from channel 27. 90

The preferred form of tool holding device and tool are shown in Figs. 4 and 5 on a scale enlarged as respects Fig. 1. In these figures the tool carrier 57 is identical with the tool carrier 46 of Figs. 1 and 2 except as respects the tool holding portion 95 thereof. In this portion of the carrier 57 the tool holding channel which intersects the lower and outer surfaces of the carrier terminates at its inner end in a cylindrical chamber 58 which extends slightly higher 100 into the metal of the carrier than the top of the tool holding channel. An adjusting plate 59 rotatively fits the upper portion of chamber 58 and carries an upstanding shank 61 which is positioned concentric with 105 the plate and recess, and extends upwardly through the plate, its upper extremity 62 being squared for engagement by a wrench. To hold the adjusting plate and its shank 110 in position a collar 63 is secured to the shank 115 by a pin 64 and bears upon the upper surface of the tool carrier 57. The lower side of the adjusting plate 59 is cut away to form a spiral adjusting rib 65, this rib engaging one or more arcuate slots 66 formed 120

125

130

in the upper surface of the cutting tool 67. By means of a bolt 68 mounted near the periphery of the carrier 57 and traversing a slot 69 formed in the tool, the latter is held 5 up against the carrier. By loosening bolt 68, the tool 67 is released for movement in its channel radially of carrier 57, and such movement, either inwardly or outwardly, is very quickly accomplished by rotation of the 10 adjusting rib 65. Under normal working conditions any adjustments required will necessitate movement of the tool 67 through a very short distance, and it is obvious that, because of the spiral character of the adjusting 15 rib 65 this slight adjustment can be accomplished with great accuracy. Measured along any given radius of adjusting plate 59 the convolutions of the adjusting rib are equally spaced from each other; 20 the pieces of metal formed in tool 67 between the arcuate slots 66 are of such thickness as to fit snugly within the spaces between these convolutions; hence the stresses set up longitudinally of the tool during its 25 cutting action are resisted not alone by bolt 68 but by the resistance of at least two of the convolutions of the adjusting rib as well. To make this resistance maximum the center of the tool holding channel lies along 30 a radius of the adjusting plate 59.

In the operation of the invention the frame plate 14 and post 15 are first rigidly bolted in place following which the frame arm 16 is loosely positioned on the frame 35 plate with the bolts 17 set in their slots but not tightened. In a similar manner a supporting plate 21 is loosely attached to the bottom of post 15. The lower centering disk 33 is now positioned in the lower end 40 of cylinder 11 and spring 34 set in place. The upper centering disk 32 is now held up below the extremity 19 of arm 16 and the tool carrier—46 or 57 as the case may be—is held below the disk. With the parts so 45 disposed, the tool shaft 25, carrying feed screw 36 and feed nut 45, is passed downwardly through its bearing in arm 16; the upper disk 32; the tool carrier 46; the lower disk 33; spring 34, and the extremity 24 of 50 shift plate 21. By rotation of hand crank 37 and feed screw 36 the feed nut is brought to a position slightly above the level at which the tool carrier is being held and the mortise 52 of catch block 51 is fitted into its 55 tenon in the nut. The feed shaft is now rotated to carry the catch block downwardly into its aperture 49 in the carrier, following which the catch plate 53 is shifted into the dotted line position of Fig. 2 to bind the 60 catch block in the carrier. By rotation of the feed screw the carrier is now lowered into cylinder 11 and the tool shaft 25 accurately centered in this cylinder by means of the disks 32 and 33, this centering action 65 resulting in such shifting of frame 16 and

supporting plate 21 as to finally position their tool shaft bearings concentric with the axis of the cylinder. The bolts 17 and 22 are now tightened, the lower end 43 of the feed screw having first been located in 70 position in supporting bar 41. The finger 28 is now swung into its channel 27 in the head of the tool shaft and bolt 31 is tightened. Crank 37 is now rotated to raise the tool carrier above the cylinder casting, in 75 which position the tool—47 or 67 as the case may be—is set in its channel in the carrier and adjusted radially thereof to make the desired cut in the bore of the cylinder. By means of crank 37 the tool is now lowered 80 to the top of the cylinder upon which it begins its work as the operator, grasping handles 29, rotates the tool shaft. The rotative power of the tool shaft is transmitted from one side of channel 35 to nut 45, and 85 thence through mortise 52 and catch block 51 to the tool carrier. As it becomes necessary to lower the tool, the operator feeds the carrier downwardly by rotation of crank 37 and feed screw 36. It is often necessary, 90 before a cylinder is completely bored, to remove the boring tool and inspect the work. For the purpose of this inspection, my invention provides for very quickly clearing the cylinder, it being necessary only to 95 swing finger 28 out of channel 27 and shift the catch plate 53 to the full line position of Fig. 2, following which the tool shaft 25, feed screw 36, tool carrier 46, and upper disk 32 may be instantly removed from the 100 cylinder casting.

While I have illustrated and described the preferred embodiment of the invention, it will be obvious that one skilled in the art may make modifications thereof without departing from the spirit of the invention; I wish therefore not to be restricted to the precise embodiment shown, except in so far as the same is limited in the appended claims.

I claim:

1. A boring machine, embodying a rotatable tool shaft, a feed screw rotatable with the shaft and with respect thereto, a tool carrier slidably mounted upon the tool shaft and rotatable therewith, a nut movable upon the feed screw, said tool carrier having a recess opening through the face thereof, an element separate from and interposed between the nut and tool carrier, 115 said element being freely detachable from the nut while the latter is upon the screw, and also being removably seated in the said recess, and a catch plate movably mounted upon the tool carrier and adapted to be moved across the said recess and over the said element whereby the said element will be locked in operative position and against detachment from the nut and tool carrier.

2. In a boring machine, the combination 130

with a suitable frame, of a longitudinally channeled tool shaft journaled therein, a feed-screw rotatably mounted in the channel of the tool-shaft and rotatable bodily with 5 said shaft, a feed nut traveling on the feed-screw and slidably fitting said channel, a recessed tool-carrier slidably mounted on the tool-shaft, a catch block removably fitting the recess of the tool-carrier and 10 releasably joined to said feed nut by a mortise formed on the catch block and engaging a tenon provided in the nut, and a catch plate secured upon the carrier and normally overlying said catch block to hold the latter in 15 its recess, said catch plate being shiftable from above the catch block to release the latter from the tool carrier.

3. In a boring machine, the combination of a frame comprising an arm arranged to 20 overlie a cylinder to be bored and to stand spaced above the same, a tool shaft depending from a tool shaft bearing provided in the arm, a bearing extending over and spaced from the other end of the cylinder 25 and in which latter bearing the other end of the shaft is journaled for free removal, an enlarged peripherally channeled head on the tool shaft bearing on the top of the arm to support the shaft, a retaining finger for 30 maintaining the shaft in its bearings, said finger being fastened to the arm and movable into and out of said peripheral channel, and a tool carrier releasably connected to the tool shaft below said arm for rotation 35 with the shaft.

4. In a boring machine, the combination of a frame comprising an arm arranged to overlie a cylinder to be bored and to stand spaced above the same, a longitudinally 40 channeled tool-shaft depending from a tool-shaft bearing provided in the arm, a feed-screw rotatably mounted in the channel of the tool shaft and rotatable bodily with said shaft, a feed nut traveling on the feed screw 45 and slidably fitting said longitudinal channel, a tool carrier slidably mounted on the tool

shaft below said frame arm, releasable connecting means whereby the tool carrier is joined to the feed nut for movement therewith, a bearing extending over and spaced 50 from the other end of the cylinder and in which latter bearing the other end of the shaft is journaled for free removal, an enlarged head on the tool-shaft bearing on the top of the frame arm to support the tool-shaft, and a device removably engaging said head and fastened to the frame arm to prevent axial movement of the tool-shaft. 55

5. A boring machine embodying a suitable frame, a tool shaft journaled therein, a feed screw mounted in the tool shaft for bodily movement therewith and for rotation therein, a tool carrier slidably mounted on the tool shaft, means whereby rotation of the tool shaft rotates the tool carrier about 60 the axis of the tool shaft and rotation of the feed screw feeds the tool carrier along the tool shaft, and a slideable and oscillating bearing in which one end of the feed screw is journaled. 70

6. A boring machine embodying a supporting structure, a tool shaft, said structure having spaced bearings in which the ends of the shaft are journaled, a feed screw mounted in the shaft for bodily movement 75 therewith and for rotation therein, a tool carrier slidably mounted on the tool shaft, means whereby the rotation of the tool shaft rotates the tool carrier about the axis of the tool shaft and rotation of the feed screw 80 feeds the tool carrier along the tool shaft, means for rotating the feed screw, a bearing in which one end of the feed screw is journaled, and a bolt and slot connection between the bearing and the said supporting structure 85 whereby the bearing will have a free movement to compensate the changes in position of the feed screw caused by the bodily movement of the feed screw.

In testimony whereof I have affixed my 90 signature.

POMPEIN BOSCH.
